TIE STRAP

Omar Summers, Seattle, Wash., assignor of one-half to Roman Yesse, Seattle, Wash.

Application July 1, 1929. Serial No. 375,003

2 Claims. (Cl. 25—131)

My present invention relates to an improved tie strap for use in connection with the erection of concrete and similar building walls. The tie strap of my invention is designed for use not only in bracing and tieing or joining the pairs of walls which provide the form or mold in which the building wall is erected, but they also perform the functions of gages in properly spacing the walls of the mold to facilitate the construction of the mold.

Means are provided whereby the tie straps may readily be assembled and attached to the opposite walls of the form, and after the concrete wall sets and the form-walls have been removed, the projecting ends of the tie straps may either be used for anchoring means of other building elements, or these ends may readily be broken off flush with the faces of the concrete wall.

The invention consists in certain novel features of construction and combinations and arrangements of parts as will hereinafter be more fully set forth and claimed. In the accompanying drawing I have illustrated one complete example of the physical embodiment of my invention, and a slightly modified type of tie strap, wherein the parts are combined and arranged according to the best mode I have thus far devised for the practical application of the principles of my invention.

Figure 1 is a perspective view of one of the metal tie straps embodying my invention. Figure 2 is a perspective view of a portion of a form for concrete walls showing the use of the tie straps. Figure 3 is a vertical sectional detail view of part of the form showing the use of the straps. Figure 4 is a sectional detail view at line 4—4 of Figure 3 showing the use of a modified type of strap. Figure 5 is a perspective view of a portion of the modified strap. Figure 6 is a plan view at one end of the preferred type of strap.

The form for the concrete wall is made up of spaced walls A and B and these walls comprise horizontally extending, tongue and groove boards, some or all of which are provided with kerfs K in their edges. The usual studding S is employed at the exterior faces of the walls of the mold or form, and gage nails N and fastening nails N' are also utilized in the erection of the form for the concrete building wall.

The preferred type of tie strap used in retaining and bracing the two walls of the form, is indicated by the numeral 1 as a light steel or iron strap which is fashioned at one side of its

center with a plurality or series of holes 2 and at the other side of its center with another series of holes 3. Near the respective ends of the strap elongated holes or slots 4 are provided; the selected holes 2 and 3 being for the reception of gage nails N and the slots 4 for the reception of the fastening nails N'.

The two series of holes 2 and 3 are gage holes and are used with the nails N for properly spacing the walls A and B of the form. Thus for instance, the innermost holes of the two series may be ten inches apart and the two outermost holes of the two series may be twelve inches apart, and a selected hole of each series is used to provide the desired spacing of the two walls 70 of the form.

In Figures 4 and 5, the tie strap 5 is fashioned with gage lugs 6 which may be substituted for gage holes 2, 3, or some of the gage lugs may be used with the gage holes in the same tie strap.

As shown in the drawing, the tie straps are deposited in the kerfs K of the wall-boards or mold boards A and B and the gage nails N are passed through the selected holes 2 and 3 to properly space the walls of the mold. The ends of the straps of course project laterally of the mold walls and these ends are attached to the studding S by the nails N'. By the use of the slots or elongated holes 4 in the straps the nails N' may be driven into the studding diagonally of the strap thus securing a more effective anchor for the ends of the straps than would the nails afford if driven at right angles to the strap. The walls of the mold are thus tied between the studding and the gage nails, and the walls are retained at the desired and required distance apart.

In Figure 4 the gage lugs 6 abut against the inner faces of the mold walls A and B and take the places of the gage nails N, but the fastening nails N' are used to secure the straps to the studding.

As indicated in Figure 2 the straps are attached at opposite sides of the studding, that is, the tie strap for one pair of boards A, B is nailed to the studding at the near side, and the strap for the adjoining pair of boards is nailed to the far side of the studding. In this manner the strain on the studding is equalized, when the wall is poured and outward pressure is exerted against the wall boards of the mold, and any tendency of the studding to twist or turn is eliminated.

After the concrete wall has set, the fastening

nails N' are extracted and the studding and mold boards are removed, leaving the tie straps in the concrete wall with their ends projecting. These projecting ends may be broken off flush with the face of the wall, or they may be used as anchoring means for other parts of the wall, as for instance a brick face for the concrete wall.

Having thus fully described my invention, 10 what I claim as new and desire to secure by Letters Patent is:—

1. A tie strap for use with wooden concrete forms consisting of a strip of sheet metal intended for placement on edge in vertical kerfs;

gauge lugs formed from the body of the strip, said lugs having considerable length and forming but a small angle where they leave the body of the strip and adapted to engage the inside wall of a form with the free ends of the lugs.

2. A tie strap for use with wooden concrete forms consisting of a strip of sheet metal gauge lugs formed from the body of the strip, said lugs having considerable length and forming but a small angle where they leave the body of the strip and adapted to engage the inside wall of a form with the free ends of the lugs.

OMAR SUMMERS.
